UNITED STATES PATENT OFFICE.

S. ROBERT SCHWARTZ AND AUGUST BOSTROEM, OF NEW YORK, N. Y., ASSIGNEES TO
SAMUEL ROBERT SCHWARTZ, OF NEW YORK, N. Y.

DESIGN FOR A PORTABLE LAMP BASE.

61,122.

Specification for Design.

Patented June 20, 1922.

Application filed September 28, 1921. Serial No. 503,991. Term of patent 7 years.

To all whom it may concern:

Be it known that we, (1) SAMUEL ROBERT SCHWARTZ and (2) AUGUST BOSTROEM, citizens of the United States of America, residing at (1) New York, in the county of New York and State of New York, and (2) New York, in the county of Bronx, and State of New York, have invented a new, original and ornamental Design for a Portable Lamp Base, of which the following is a specification, reference being had to the accompanying drawing, forming part thereof.

The figure is a perspective view of a portable electric lamp having a base showing our new design.

We claim:

The ornamental design for a portable lamp base, as shown.

In testimony whereof, we have signed our names to this specification in the presence of two subscribing witnesses, this twenty-fifth day of May, 1921.

S. ROBERT SCHWARTZ.
AUGUST BOSTROEM.
